UNITED STATES PATENT OFFICE.

AUGUST V. BAYER, OF ST. LOUIS, MISSOURI, ASSIGNOR TO BAYER STEAM SOOT BLOWER COMPANY, OF ST. LOUIS, MISSOURI, A CORPORATION OF MISSOURI.

SOOT-BLOWER FOR BOILERS.

1,036,953.

Specification of Letters Patent. Patented Aug. 27, 1912.

Application filed April 22, 1912. Serial No. 692,273.

To all whom it may concern:

Be it known that I, AUGUST V. BAYER, a citizen of the United States, residing at St. Louis, State of Missouri, have invented certain new and useful Improvements in Soot-Blowers for Boilers, of which the following is a full, clear, and exact description, reference being had to the accompanying drawings, forming a part hereof.

10 My invention has relation to improvements in soot-blowers for boilers, and it consists in the novel details of construction more fully set forth in the specification and pointed out in the claims.

15 In the drawings, Figure 1 is a side elevation of a portion of a water-tube boiler and furnace, with parts broken away showing my invention applied thereto; Fig. 2 is a vertical transverse section on the line 2—2 of Fig. 1; Fig. 3 is a horizontal section on the zig-zag line 3—3 of Fig. 1; and Fig. 4 is a detail showing in elevation the sectional formation of the outer plate through which the nozzles play.

25 The present invention is an improvement on the device forming the subject-matter of my pending application for soot-blower attachment, filed March 4, 1912, Serial Number 681,379; and while contemplating the 30 several objects and possessing the various advantages identified with said attachment, the improvement herein dispenses with the moving plate or shield operating in conjunction with the blower nozzle to cover up the 35 wall opening through which such nozzle plays.

The object therefore is to provide stationary means for keeping covered the opening traversed by the blower nozzle, so that 40 air may be excluded from the interior of the boiler-furnace during the blowing of the boiler for purposes of cleaning the tubes of soot, ashes, and other accumulations. In the present invention such air-excluding 45 means are directly identified with the stationary member of the hollow joint by which the nozzle is carried.

In detail the invention may be described as follows:

50 Referring to the drawings, F represents the side furnace-wall of a well-known type of water-tube boiler (the Babcock and Wilcox), and T the inclined tubes entering into the construction of the water-tube section of 55 the same. As well understood in the art,

the side wall is provided with a recess or opening O opposite the tubes, said opening being closed by a wall-plate P provided with laterally elongated (usually elliptical) openings or slots s (bounded by a beveled flange b) through which hand-operated blower nozzles are inserted when blowing or cleaning the boiler by the old hand method. In the present case these slots are utilized to accommodate the steam nozzles 1 of a permanent installation, said nozzles terminating in spray-heads 2 opposite the spaces between the tubes T, for the projection of the cleaning fluid (steam as a rule) by which the boiler is blown from time to time and the tubes cleaned of accumulations of soot, cinders, ashes, dirt and other foreign material. The nozzles in practice have a definite range of oscillation across the openings s in planes substantially parallel to the boiler tubes, so as to take in as large a section of the tubes as possible during the blowing operation.

Any means for imparting oscillation to the nozzles may be adopted, the mechanism shown not being herein claimed, constituting as it does the subject-matter of a distinct application. It may, however, be briefly referred to in order to explain at least one mode of actuating the nozzles. Mounted centrally in front of the wall-plate P is a fixed riser 3 which is supplied with steam from the steam feed-pipe 4. The pipe 4 preferably draws its steam supply from the shell or drum S of the boiler, the connections not being shown. Mounted to one side of the riser is a rocker-bar 5 provided with an operating handle 6, the bar having distributed thereon a series of lever arms 7 which are coupled through the links 8 to the lever-arms 9 of the rotatable members 10 of the hollow steam joints 10' from which lead the nozzles 1. The joints are mounted at the inner ends of the short tubes or branches 11 carried by the riser 3, through which tubes the steam flows into the joints and thence into the nozzles 1 and spray-heads 2. The axes of rotation of the joints (that is, of the rotatable members 10) are at right angles to the tubes T (Fig. 1) so that when the rocker-bar 5 is rocked back and forth, the nozzles have imparted to them a swinging movement or oscillation substantially parallel to the boiler tubes. This feature however, is not herein claimed.

The dimensions of the slots s formed in

the wall-plate P and through which the nozzles 1 project, are more than sufficient to allow for the necessary oscillation or traverse imparted to the nozzles; and in the present embodiment of my invention I prefer to place a second plate P' in front of the wall-plate P, in which are formed inclined slots s' opposite the slots s, of just sufficient width to allow for the free play or traverse of the nozzles, and of a length equal substantially to the length of the traverse of the nozzle. It is of course desirable that the slots s' (and their registering slots s of the wall-plate P) should be kept permanently covered so as to exclude from, and prevent ingress of atmospheric air into, the furnace, especially while the boiler is being blown, such air tending not only to chill the tubes, but to condense the steam employed for cleaning purposes. In the present improvement this exclusion of atmospheric air is accomplished by the flange 10" forming an extension of the outer stationary member or casing 10' of the hollow joint (the member 10 constituting the inner rotatable member of said joint), said flange being in the nature of an apron or shield, and being bolted directly to the plate P'. Within this shield or apron the nozzle has ample room to oscillate, and a sliding plate mounted on the nozzle across the slot, such as shown in my pending application aforesaid is unnecessary; besides, the present improvement is much more practical and eminently more desirable. The flange (10") engaging the plate P' forms a tight joint therewith, and likewise a chamber a for ample accommodation of the oscillating nozzle 1. In practice of course, the plate P may be dispensed with, but as it is already built in the walls of the majority of existing furnaces, it need not be disturbed. In my present improvement therefore, the air-excluding member, flange or shield for the slot s' is directly identified with the stationary member of the hollow swing-joint. In the claims, the "opening" across which the nozzle is stated to operate, is to be understood as the slot s' (or its equivalent) in the plate P' (or its equivalent) through which the nozzle passes and which it traverses in its oscillations. The flange 10" is herein identified with the peripheral walls of the outer joint casing 10', the ends of the latter being closed by the rotatable member 10. The details of the hollow joint in particular not here referred to are not claimed, forming as they do, the subject-matter of my pending application for boiler-cleaners filed Dec. 1, 1911, Serial 55 Number 663,350.

No particular method of fastening the plate P' is here claimed. The plate is bent to conform to the contour of the wall-plate P and the converging walls of the outer portions of the window or opening O. Refer-

ring particularly to Fig. 3, advantage is taken of the metal strips t identified with the wall-plate P and present in existing boiler-furnaces. By bending the sheet composing the plate P' so as to engage the outer edges of the strips t, the spring of the metal of the sheet will suffice to keep the plate P' wedged between the strips. If necessary, nails may be driven through the outer flaring portions or wings of the plate into the brick-work. To better adjust the length of the plate P' to the heights of the openings O of different boiler furnaces, I prefer to first place a narrow section P'' at the top of the opening (Fig. 4), then lap the main section P' over the plate P'', the adjustment as to height being permitted to be made by the recesses r in the section P'', the securing bolts m carried by the main plate P' traversing said recesses during the adjustment. By then driving home the nuts on the bolts, the connection is readily made. Once the plate P' is in position, it may be regarded as constituting a part of the furnace wall through which the blower nozzle plays.

Having described my invention, what I claim is:

1. In combination with a boiler-furnace wall provided with an opening, a hollow joint adjacent said wall, a blower nozzle leading from the joint and operating through said opening, and means on the joint stationary relatively to the nozzle for permanently covering said opening to prevent access of air to the boiler.
2. In combination with a boiler-furnace wall provided with an opening, a hollow joint in front of said wall opposite the opening, a blower nozzle oscillating about an axis in the joint and traversing said opening, and means on the joint stationary relatively to the nozzle for permanently covering said opening to prevent influx of atmospheric air to the boiler.
3. In combination with a boiler-furnace wall provided with an opening, a hollow joint in front of said wall opposite said opening, a blower nozzle oscillating about an axis in the joint and traversing said opening, and a formation on the joint stationary relatively to the nozzle secured to said wall around the opening and forming a permanent cover for said opening.
4. In combination with a boiler-furnace wall provided with an opening, a hollow joint comprising an outer stationary casing and an inner rocker member positioned in front of said opening, a nozzle connected to the rocker-member and operating through the wall of the casing and projecting through and oscillating across the wall-opening aforesaid, and a formation on the joint casing engaging the furnace wall around the opening therein and forming a permanent cover therefor.

5. In combination with a boiler-furnace wall provided with an opening, a hollow joint comprising an outer stationary casing and an inner rocker-member closing the ends 5 of the casing, positioned in front of said opening, a nozzle connected to the rocker-member and operating through the casing wall and projecting a cleaning fluid through the opening in the furnace-wall, and a for-
10 mation on the peripheral walls of the hollow joint casing engaging the furnace wall and forming a chambered cover around the opening therein to exclude atmospheric air from the boiler, the chamber of the cover affording ample play for the oscillations of the 15 nozzle.

In testimony whereof I affix my signature, in presence of two witnesses.

AUGUST V. BAYER.
